UNITED STATES PATENT OFFICE.

JOHN A. BOEHRINGER, OF SPRINGFIELD, NEW YORK, ASSIGNOR TO STAR CHANDELIER CO., INC., OF NEW YORK, N. Y., A CORPORATION OF NEW YORK.

DESIGN FOR A SPREADER FOR A LIGHTING FIXTURE.

Application filed March 17, 1927. Serial No. 21,165. Term of patent 3½ years.

To all whom it may concern:

Be it known that I, JOHN A. BOEHRINGER, a citizen of the United States, residing at 145-85 Aberdeen Street, Springfield, Long Island, in the county of Queens and State of New York, have invented a new, original, and ornamental Design for a Spreader for a Lighting Fixture, of which the following is a specification, reference being had to the ac-

companying drawing, forming part thereof.

The figure is a perspective view of a spreader for a lighting fixture, showing my new design.

I claim:

The ornamental design for a spreader for a lighting fixture, as shown.

JOHN A. BOEHRINGER.
